UNITED STATES PATENT OFFICE.

JAN SOWALSKI, OF CHICAGO, ILLINOIS.

DESIGN FOR A WINDOW.

55,539.

Specification for Design.

Patented June 22, 1920.

Application filed December 8, 1919. Serial No. 343,428. Term of patent 3½ years.

To all whom it may concern:

Be it known that I, JAN SOWALSKI, a citizen of Poland, residing at Chicago, in the county of Cook and State of Illinois, have invented a new, original, and ornamental Design for a Window, of which the following is a specification, reference being had to the accompanying drawings, forming a part thereof.

The figure is a view of a window, showing my new design.

I claim:

The ornamental design for a window, as shown.

JAN SOWALSKI.
